UNITED STATES PATENT OFFICE.

PAUL LUCAS, OF BLOOMFIELD, IOWA.

NECKTIE-HOLDER.

No. 920,595.

Specification of Letters Patent.

Patented May 4, 1909.

Application filed November 7, 1908. Serial No. 461,533.

To all whom it may concern:

Be it known that I, PAUL LUCAS, a citizen of the United States, residing at Bloomfield, in the county of Davis and State of Iowa, have invented new and useful Improvements 5 in Necktie-Holders, of which the following is a specification.

This invention relates to necktie holders, the object of the invention being to provide 10 a simple, neat, inexpensive and effective device of this kind adapted to engage and be held in position by the front collar button and to engage the bow or knot of the tie to hold the latter in position against slipping 15 in any direction, as well as to keep said knot or bow projected a desirable distance forward from the flaps of the collar for a maximum and presentable display.

The invention consists of the features of 20 construction, combination and arrangement of parts hereinafter fully described and claimed, reference being had to the accompanying drawing, in which:—

Figure 1 is a perspective view showing the 25 application of the invention, the tie being indicated in dotted lines. Fig. 2 is a perspective view of the holder shown in Fig. 1. Fig. 3 is a similar view of a modified form of holder.

The holder shown in Figs. 1 and 2 is de- 30 signed especially for use when a stiff-bosomed shirt is worn, and is composed of a single piece of spring wire, which may be nickelplated, silver plated or gold plated to 35 render it attractive and protect it against rust. The holder has its central portion bent to provide a button engaging clasp 1, which is closed at its upper end and sub- 40 stantially of diamond form, the lower ex- tremities of its lower converging arms being spaced to provide an entrance passage 2. From this point the intermediate portions 45 of the wire are bent upwardly on opposite sides of the clasp in the form of uprights or branches 3 which terminate at or near the upper end of the clasp. The uprights or 50 branches 3 thus formed serve as supports for a pair of forwardly projecting convergent arms 4 formed by the extremities of the wire, 55 which arms terminate a proper distance in advance of the clasp to hold the bow or other tie set forward a desired distance from the flaps of the collar. The extremity of one of the arms 4 is tapered and projected at an upward and forward angle to form a 60 prong or spur 5 to engage the rear portion

of the knot or bow of the tie, and to thus fasten the same in position against shifting relative to the collar, while the end of the other arm 4 is coiled to embrace the first 60 named arm, as indicated at 6, or otherwise suitably fastened thereto.

In the use of the device as thus constructed the clasp is engaged with the front collar button by forcing it downward on the shank 65 of the button, as clearly shown in Fig. 1, the spring action of the sides of the clasp serving to hold the device in position. The tie is then applied and engaged with the prong or spur 5, by which it will be secured against 70 vertical or lateral movement. As the prong or spur 5 is arranged at the forward ends of the arms 4 it will be apparent that the bow or other tie will be spaced from the button and flaps of the collar, thus preventing 75 objectionable pressure upon the button and neck of the wearer, while at the same time keeping the knot or bow set forward for a permanent and attractive display.

The clasp 1 has sufficient engaging force 80 to fasten the holder in position upon the collar button against any liability of casual displacement when a stiff-bosomed shirt is worn, by which the degree of movement of the flaps of the collar and the button is 85 limited, but the form of the invention shown in Fig. 3 is preferable when a negligée or soft-bosomed shirt is worn, as affording a 90 secure connection between the holder and button to prevent disconnection of the holder 95 in use from the movement of the parts allowed by the greater flexibility of the bosom. In this form of the invention shown in Fig. 3, the construction is the same as that described with reference to the form shown 95 in Figs. 1 and 2, except as to the clasp portion, which in Fig. 3 is illustrated as composed of a pair of upwardly converging clamping arms adapted to bear against the opposite sides of the shank of the button, 100 which arms carry a forwardly and downwardly projecting U-shaped clamping member 1^b, the lower diverging ends of the arms 1^a forming an entrance space or passage 2^a. The holder thus constructed is slipped down 105 upon the shank of the button, which enters between the arms 1^a through the passage 2^a, whereby the shank of the button is clamped, the head of the button being brought to lie between the upper ends of the arms and the 110 spring clamping member 1^b, the pressure of which latter will serve to hold the head

of the button clamped against the arms and the holder in position against any possibility of casual displacement under ordinary service.

5 From the foregoing description, the construction, mode of use and advantages of my improved necktie holder will be readily understood without a further extended description, and it will be seen that its construction enables it to be manufactured and sold at a comparatively low cost.

Having thus fully described the invention, what is claimed as new is:—

15 1. A necktie holder formed of a single piece of spring wire, said holder comprising a central clasp portion having an entrance at the lower end thereof, uprights arranged on opposite sides of said clasp portion, and straight converging arms projecting for-
20 wardly from the upper ends of said uprights and united, one of said arms being extended to provide a straight spur or prong project-

ing at an upward and forward angle therefrom.

2. A necktie holder formed of a single 25 piece of wire, said holder comprising a central clasp portion having an entrance at the lower end thereof, uprights arranged on opposite sides of said clasp portion, a forwardly and downwardly projecting clamping member upon the upper end of said clasp portion, straight converging arms projecting forwardly from the upper ends of the uprights and united, and a straight spur projecting at an upward and forward angle 30 from the connected point of the arms and forming an extension from one of said arms.

In testimony whereof I affix my signature in presence of two witnesses.

PAUL LUCAS.
